UNITED STATES PATENT OFFICE.

THOMAS BARBOUR, OF BELFAST, IRELAND.

HACKLING MACHINE.

Application filed June 3, 1926, Serial No. 113,520, and in Great Britain June 16, 1925.

This invention relates to hackling machines and the methods of hackling flax, hemp, jute and analogous fibres, and the object of the invention is to enhance the hackling action by a novel arrangement of the pins.

In the accompanying drawings:

Figure 1 is a diagram showing an example of pins alternately spaced at different distances apart in accordance with this invention;

Fig. 2 is a diagram showing the regular spacing of pins according to the existing practice; and

Fig. 3 is a diagram showing the portions of a piece of flax which receives hackling during one complete lift of the channels in a machine that is provided with regularly spaced pins and in which no differential motion is used for varying the speeds of the hackles.

Heretofore the arrangement usually adopted has been to cause pieces of the material to be hackled, to be gripped between suitable plates which rise and fall, and during the course of their upward and downward movement allow the material to pass between revolving sheets to which are attached pins or combs, and thus the material is hackled or combed out.

In order to arrive at a proper degree of hackling the pins or combs are graded in fineness along the machine and at every lift of the grippers on arriving at the top point they (the grippers) are mechanically pushed along, so that on the redescent the material is presented to a different set of pins with a finer gradation. These pins are further regularly grouped and pitched in their relative positions to each other, so that each pin on each portion of the revolving sheets may strike into a different portion of the material.

With the customary grouping of pins as referred to above under existing normal working conditions only portions of the flax are hackled at all on the first few series of graded pins, and the flax thus unhooked may pass on so as to receive initial treatment from a series of pins finer than is consistent with initial treatment thereby causing undue breakage of fibres and loss of material.

According to this invention the pins in each group are so arranged that each pin is made to intersect that space which prevails

when the pitching of the pins is spaced regularly.

This is conveniently effected by spacing the pins irregularly in each hackle, the spacing and irregularity of pitch being controlled by the number of hackles and pitch of pins in a group. By the term "group" is meant the number of pins which follow one another in a diagonal path in each succeeding hackle before the last pin in that group comes into the same vertical row that is occupied by the last pin of the preceding group.

For this purpose the pins in each bar may be alternately spaced at different distances apart, the two unequal constituents constituting the pitch, the spacing and pitch being controlled by the number of hackles in a group. For example if the hackles are grouped in a series of 8 and the pitch is two inches, (pitch in this instance meaning the sum of the distances A + B as below) the narrower spaced pins which may be referred to as A would be half the pitch minus half of the pitch divided by the number of hackles in the group. The wider space which may be referred to as B would be half the pitch plus half of the pitch divided by the number of hackles in the group. The formula would be as follows:

$$A = \frac{P}{2} - \frac{1}{2} \left\{ \frac{P}{\text{grouping}} \right\}$$

and

$$B = \frac{P}{2} + \frac{1}{2} \left\{ \frac{P}{\text{grouping}} \right\}$$

Instead of the irregularity being the difference between A and B it may be various, for example the pitch may be subdivided into any number of equal, or unequal subdivisions, hence the formula whilst remaining the same in principle would require adjustment to comply with whatever particular pitch and irregular subdivision of pitch be under consideration.

The reason for spacing the pins irregularly is to cause each pin in each group to travel along a separate path with the result that, supposing the hackles to be arranged in groups of 8 with 12 pins in each hackle, the pins will describe 96 separate paths. The same or closer pitching of the paths of the hackle pins through the flax can thus be obtained together with a shorter grouping i. e. the hackles can be grouped

in 6 or 8 instead of 12 or 24. This shorter grouping permits of time for at least one hackle of each kind in the group to penetrate the flax during each lift and thus all 5 portions of the flax get hackled. When the hackles were grouped in 24 then 24 bars had to pass before a hackle of each sort had penetrated the flax, and for this reason many parts of the piece never received hackling 10 until they had passed the first or second sets of hackles.

In the example shown in Fig. 1, the hackles indicated by the horizontal lines have their pins indicated by the circles arranged in groups of 8 as indicated by the dotted lines A indicating the distance between the narrower spaced pins, B the distance between the wider spaced pins and P the pitch, and it will be seen that by spacing 20 the intermediate pins *a* irregularly as shown in Fig. 1 each such pin will intersect a space with the result that twice as many hackling paths are obtained in Fig. 1 as are obtained by the existing method of spacing 25 as shown in Fig. 2, in which the pins are arranged in groups of four as indicated by the dotted lines, although the pins number the same in the aforesaid figures.

In the ordinary method of hackling all 30 portions of each individual piece of flax do not receive equal pinning, owing to the fact that the flax in descending and rising has in itself a motion relative to the motion of the pins, so that each succeeding hackle 35 striking into the descending or rising material, travels a path differing in dimensions from that travelled by its immediate predecessor. Owing to the grouping, the striking in points during the fall and rise lie along 40 a line which forms an angle (depending on the grouping) with the horizontal, and ordinates drawn from the striking in points to the horizontal represent the path of each pin through the flax. During the dwell the 45 striking in points lie along the horizontal,

and their path through the flax is indicated by lines drawn at right angles to the horizontal—thus those portions of the flax subjected to treatment by the pins are clearly outlined, while the spaces on which no lines appear show those portions of the material which pass on to the following tools, without having been touched by the pins at all. The percentage of such spaces to the total area of the flax is, under ordinary conditions, undesirably large. The above is illustrated 50 in Fig. 3 which shows the portions of a piece of flax which receive hackling during one complete movement of the channels with the machine running at 8 lifts per minute and 60 the sheets revolving at 12 revolutions per minute, the hackles being grouped in 24. C indicates the length of the holder, D the length of the flax, the points where the pins strike into the flax are indicated by the 65 circles E; the hackling that is done during the dwell of the channel is shown by the dotted lines F; the hackling that is done during the fall of the channel is shown by the dot and dash lines G; the hackling that is done during the rise of the channel is shown by the full lines H; and the un-hackled portions of the flax are represented by the blank spaces J.

What I claim as my invention and desire 75 to secure by Letters Patent in the United States, is:—

A hackling machine having a series of hackles each provided with a row of pins, the pins of the successive hackles being arranged in diagonal paths, and said paths being spaced apart different distances, in order that some of the pins of each hackle are made to intersect spaces which would prevail if the pins of the hackles were 80 spaced apart regularly.

In witness whereof I have signed this specification.

THOMAS BARBOUR.
